LOCK

Franklin H. Harp, Seattle, Wash., assignor to
 Frank E. Best, Inc., Seattle, Wash., a corpora-
 tion of Washington

Application April 17, 1933, Serial No. 666,520

2 Claims. (Cl. 70—216)

My invention relates to locks and the general object of my invention is to improve the construction of locks generally and to render the same more efficient and reliable in operation.

5 The invention as herein disclosed is embodied in a door lock of the form commonly termed a "unit lock" but it will be understood that the invention is not to be restricted to so called "unit locks" but that many features of the same 10 are applicable to locks of other types.

An object of my invention is to provide a lock having a knob, thumb piece or like actuating device connected with the lock mechanism by shear or friction means whereby an attempt to force 15 the lock by unauthorized persons will result in the shearing off or slippage of parts before the lock will be damaged. When a door knob having a lock therein is thus provided with shear or slippage means it is necessary to provide throw 20 mechanism connecting said lock with a bolt, which throw mechanism will permit the knob to be rotated without retracting the bolt or without damaging said throw mechanism in the event the shear means is sheared off or slippage of 25 the friction means is compelled, said throw mechanism always being capable of retracting the bolt when the lock is operated by a proper key. I provide a throw mechanism accomplishing this purpose.

30 Another object is to provide a lock which may readily be installed on a right or left hand door.

Other and more specific objects of the invention will be apparent from the following description taken in connection with the accompanying drawings.

35 In the drawings Figure 1, is an elevation with certain cover plates and knob parts removed, of a lock constructed in accordance with my invention.

40 Fig. 2 is a sectional view of said lock substantially on broken line 2—2 of Fig. 1, parts being shown in elevation.

Fig. 3 is a detached view partly in section and partly in elevation through a knob lock mechanism embodied in this lock, showing parts of the throw mechanism connected therewith.

45 Fig. 4 is a detached view partly in elevation and partly in section showing parts of the throw mechanism in slightly spaced apart relation.

50 Figs. 5 and 6 are diagrammatic elevations on a larger scale substantially on broken line 5—5 of Fig. 4, of the throw parts shown in Figs. 3 and 4, showing different operative positions of the several parts.

55 Fig. 7 is a fragmentary view partly in section and partly in elevation illustrating the operation of a bolt member embodied in this lock, the bolt member being shown in fully retracted position and a bolt blocking member being shown, partly 60 by dotted lines, in a blocking position.

Figs. 8 and 9 are detached plan views of two types of bolt retracting members embodied in this lock.

Figs. 10 and 11 are detached elevations respectively of two tubular supporting members for the 5 knob shanks.

Fig. 12 is a detached plan view of a member which is used to secure the knob shanks in assembled relation in the lock.

Like reference numerals designate like parts 10 throughout the several views.

In the following description I first describe a preferred form of door knob having shear means constructed in accordance with my invention.

One manner of constructing a door knob having shear means adapted to shear off before damage is done to other parts of the lock is illustrated in Figs. 1 and 3. This knob embodies a knob cylinder or lock case 20 recessed as at 21 to receive a primary lock 22, preferably of pin tumbler type. The cylinder 20 forms a body about which the knob is built. The knob may consist of an inner shell portion 23 and an outer shell portion 24. The outer shell portion 24 preferably forms the outer end and peripheral portion of the knob and overlies a portion of the end of the cylinder 20 and has an inwardly protruding annular rib 25 fitting over the end of the cylinder 20, said rib serving as a means for correctly positioning the shells relative to the outer end of the cylinder. The end of the outer shell is further cut away as at 26 to afford access to the end of the lock. The inner shell portion 23 is partially disposed within the outer portion and is frictionally engaged by the outer shell portion so that the two shell members will turn together as a unit and said inner shell portion has a neck 27 which is press fitted tightly onto the cylinder member 20 and further has an inwardly extending flange portion 28 which overlaps the marginal part of one side of an external annular flange 30 which is integral with or otherwise fixedly secured to a knob shank 31. The flange 28 of the inner shell 23 is secured to knob shank flange 30 by a shear pin 32. The knob shank 31 is arranged to retract a lock bolt as hereinafter described, when it is turned. If a pipe wrench or like tool is placed on the outer shell portion 24 of the knob and an attempt is made to turn the same the shear pin 32 will be sheared off and permit the knob including the two shell members 23 and 24 and the lock case 20 with primary lock 22 therein, to turn without turning the knob shank 31, thus making it impossible to operate the lock bolt or break the lock mechanism by 50 forcibly turning the knob.

When a shear means of the type just described is used it is obviously necessary to have a new shear means installed if the shear means is sheared off. I can overcome the necessity for a 60

repair of this nature by providing between the knob and the knob shank a friction means which replaces the shear means, said friction means affording a great enough friction so that the knob 5 and the knob shank will be effectively locked together for all ordinary operation of the lock and at the same time allowing the knob to be turned while the knob shank remains stationary if an attempt is made to force the lock.

10 The primary lock 22 which is disposed in the cylinder 20 may be of a well known pin tumbler type. The cylinder 20 has a flange portion 51 near its inner end which separates the compartment in which the primary lock 22 is disposed 15 from a compartment 52 in which throw mechanism is positioned. This throw mechanism embodies a throw disc 53 having two throw pins 54 rigid therewith and protruding telescopically into the primary lock 22 whereby the throw disc 20 53 may be turned by the insertion of a key in the primary lock. A retainer plate 55 secured to the housing flange 51 retains the disc 53 in place and has an opening 56 therein to afford clearance for the two throw pins 54. The disc 53 has a crank 25 pin 57 protruding from the inner face thereof and extending through an elongated hole 58 in one end of a throw link 60. The other end of the throw link 60 has a hole 61 which fits over a throw lever pin 62 on a throw lever 63 which is 30 secured to the end of a throw spindle 64, preferably of square cross section, by which latch mechanism of a form hereinafter described is operated. The throw link 60 is thus positioned so that it operates freely between the throw lever 35 63 and the throw disc 53. When the throw disc 53 is in the normal inoperative position which it must occupy at all times when the key is removed from the lock the crank pin 57 on said throw disc 53 will be in axial alignment with the throw 40 spindle 64 and both will coincide with the common axis of the knob spindle and the knob. In the event the shear pin 32 is sheared off and the knob is turned without turning the knob shank, when the throw pin 57 and throw spindle 64 are 45 thus positioned with their axis common to the axis of the knob and knob shank, the throw disc 53 will likewise be free to rotate on this common axis but the knob spindle 64 will not be rotated and consequently the latch mechanism will not 50 be retracted. This allows the shear pin 32 of a knob to be sheared off and the knob to be rotated by an unauthorized person when the latch mechanism is locked without operating the latch mechanism or damaging any part of the same, the 55 shear means and throw means thus cooperating to prevent the lock from being opened or seriously damaged by persons seeking to force the lock.

If the throw disc is rotated by insertion of the proper key in the lock the crank pin 57 moving 60 around on the arc of a circle, see Figs. 5 and 6, will exert a thrust on the link 60, which thrust will be transmitted to the throw lever pin 62 thus moving the throw lever 63 and turning the throw spindle 64. The turning of the throw spindle 64 65 may retract a latch bolt in a manner hereinafter described. The elongation of the hole 58 in the throw link 60 affords some lost motion between the crank pin 57 and the throw link 60 and insures that the thrust exerted on the throw link 70 will be sufficiently off center to impart a torque to the spindle 64. The oversize of the hole 58 of the throw link 60 also takes care of any inaccuracy of the positioning of the throw lever pin 57 with respect to the axis of the knob and the 75 knob shank and makes it possible to rotate the

knob without turning the throw spindle even though the throw lever pin is positioned slightly off center relative to the axis of the knob and knob shank.

A knob-shank bearing-tube 65, Figs. 1, 2, 10 and 11, is provided for the reception of the knob shanks 31. This bearing tube 65 is supported in a bearing tube holder 66 which is secured, as by screws 67 to a lock case 68. A set screw 70 serves to clamp the bearing tube 65 to the bearing tube holder 66. The bearing tube 65 is cut away as at 71 to afford clearance for the operation of a plurality of throw members 72, 73 and 74. The two throw members 72 and 73 are shaped to fit within counterbored and notched portions 75 15 in the ends of the knob shanks 31 whereby they will be moved rotatively by the turning of these knob shanks. These two throw members are hereinafter termed knob throws. When a primary lock 22 is provided in one knob only, as 20 illustrated in Fig. 2, then only one lock throw 74 is provided and this lock throw is operated by the single spindle 64. Suitable springs, herein-after described always tend to return the locking spindle to normal position when it is released 25 and the primary, pin tumbler lock requires that the key must always be brought back to the same position before it can be withdrawn from the lock this always insures correct positioning of the primary lock throw parts and the spindle when 30 the lock is not in actual use. The spindles 63 may be of square cross section, the openings 31' 35 in the knob shanks may be circular, the openings 72' and 73' in the hub portions of the knob throws 72 and 73 may also be circular so that the knob and knob shanks are not rotatively connected with the spindle. The opening 74' in the lock throw 74 may be square whereby the lock throw 74 will be controlled by the turning of the spindle which passes therethrough.

Two pairs of slots 84, Fig. 10 are provided in the bearing tube 65 and extend partially around said bearing tube 65 adjacent opposite ends of the cut away portions 71 for the reception of flat prongs 85 on U shaped clips 86, Fig. 12, by which the knob shanks 31 are secured in assembled relation within the bearing tube 65, the said prongs 85 fitting within annular grooves 87 in the knob shanks. These clips form a very efficient means for holding the knob shanks and permit a very quick and easy assembly or disassembly without the use of special tools. A quickly and easily removable slide plate 88 forms a closure at the rear end of the lock case. This slide plate also retains the clips 86 in proper position when the lock is 50 assembled.

The bearing tube holder 66 has two arms 69 protruding from the upper end thereof at diametrically opposite locations and positioned in contact with the sides of the bearing tube. 60 These arms 69 each having a plurality of spaced apart holes 90 therein and the bearing tube is correspondingly provided with holes 91 which register with the holes in the arms 69. The knob shanks 31 are also provided with holes 92 which 65 register with the holes in the arms 69 and bearing tube 65. These several holes constitute a part of the means for locking the knob shanks 31 against turning. Only one set of these holes for each knob shank need be occupied by pins for 70 locking the knob shanks. The elements which lock into these holes 90, 91, 92 are in the nature of pin means 93 in a locking slide 94. The slide shown in Fig. 1, 2 and 7 may comprise a flat face portion 95 to which the pin 93 is secured 75

and a flat shank portion 96 positioned at right angles to the face portion 95 and guided for sliding movement in notch means 97 which is provided in guide means 98 which is fixedly secured 5 to the lock case 68. A slide retainer bracket 100 is provided for holding the slide shank 96 down. The top edge of the slide shank 96 has a shoulder 101 thereon for engagement with the forward edge of the slide retainer bracket 100 whereby rearward movement of said slide is limited and a notch 102 is provided in the top edge of said slide shank just forward of the shoulder 101 for the reception of an arm 103 on a thumb turn operated spindle 104. An upright post 105 having 10 a pin 106 on the top end thereof forms a positioning and bearing means for the spindle 104 and said spindle 104 is further supported for rotation within the cover 107 of the lock case 68. The lower edge of the slide shank 96 has two or more 15 notches 108 provided therein for engagement by a V shaped detent element 109 provided on a flat spring 110 see Figs. 2 and 7. Obviously oscillating movement of the thumb turn spindle 104 will move the slide back and forth and cause the pin 20 93 to enter or to be withdrawn from the hole 92 in the knob shank 31 thus locking or unlocking the knob as respects turning movement thereof.

An indicator 161 may be secured by a pivot 162 to the bracket member 98 and engaged by an inclined front edge 163 on the locking slide 94. When locking slide 94 is in locking position the indicator is moved out through a hole 164 in the lock case, thus indicating visibly that the lock is in a locked condition. When the locking slide 94 25 is retracted a spring 165 retracts the indicator 161 and causes it to disappear inside of the lock case.

The lock case 68 is provided with a face plate 130 having an opening 131 for operation of a bolt member 132 of conventional hollow type which is mounted on a pivot 133. A bolt trip 134 Figs. 1 and 7 is secured within the bolt member 132 by a pivot 135 and has a catch portion 136 which projects out of the bolt member into the 30 lock housing. A torsion spring 137 urges the bolt trip 134 into the position shown in Fig. 2. This bolt trip 134 has another pivot 138 which is connected with a sub-tongue member 139 which extends into the lock case and rests upon the bracket 100. The sub-tongue member 139 has a slot 140 engaged by a finger 141 on a tongue plate 142 which is guided for sliding movement in the lock case. A spring 143 engages with a lug 144 on the tongue plate 142 and urges said tongue plate 142 toward the forward end of the lock housing. The central portion of the tongue plate 142 is cut away for clearance purposes and two wings 145 are provided on the rear end of the tongue plate for engagement with the several 35 throw members which are operated either by turning of the knobs or by turning of keys in the locks. When one of the throw members 72, 73, or 74 is turned in either direction it will engage with one of the wing members 145 and simultaneously retract the tongue plate 142, the sub-tongue 40 139 and the bolt 132. When the bolt 132 is retracted by pressure due to the closing of the door the slot 140 in the sub-tongue allows retractile movement of the bolt and sub-tongue without moving the tongue plate or turning the knobs thus saving wear on these parts. A compression spring 158 engages with a member 159 in the bolt member 132 and yieldingly urges said bolt

member 132 outwardly. The action of the spring 137 urges the bolt trip 134 into a position in which the catch member 136 is moved down into the path of a bolt blocking member 146 which is carried on a pin 147 and partially guided in 5 the bracket 100. The pin 147 extends out through the side of the lock case and is positioned where it may engage a door jam or plate 148 and be moved thereby into obstructing position relative to the catch member 136 of the bolt trip 134. A 10 spring 150 exerts an outward pressure on the pin 147 and blocking member 146. When a pull is exerted on the sub-tongue 139 the first movement produced by this pull will be a rocking movement of the bolt trip 134 which will move the catch 15 member 136 out of the path of the blocking member 146 after which, further retractile movement of the sub-tongue 139 will retract the bolt 132 into a position as shown in Fig. 7. If an attempt is made to press the bolt 132 back when the door 20 is closed and the blocking member 146 is in obstructing position the catch member 136 will engage the blocking member 146 as shown in Fig. 8, and block the retraction of said bolt. This is a safety feature which prevents opening of the lock 25 by insertion of a thin tool between the face plate 130 and the strike plate 151 of the lock. When the door is not fully closed the blocking member 146 will not be in obstructing position and the bolt 132 may be retracted by pressure, in the usual 30 way, as by the striking of said bolt against a strike plate in the closing of the door. For this reason the blocking member 146 does not interfere with the normal operation of the bolt 132.

The foregoing description and accompanying 35 drawings clearly disclose a preferred embodiment of my invention but it will be understood that this disclosure is merely illustrative and such changes in the invention may be made as are fairly within the scope and spirit of the following claims. 40

I claim:

1. In a lock of the class described, a knob mounted for rotation, a primary lock mechanism in said knob, a rotatable key plug in said primary lock mechanism, a throw pin on the end of said key plug movable in a circular path by rotation of the key plug and normally positioned substantially coaxially of said knob, a lock spindle positioned in substantially axial alignment with said knob and said throw pin, and throw means connecting said throw pin with said lock spindle, said throw means having a pivotal connection with said throw pin whereby said knob may be turned without turning said lock spindle. 50

2. In a lock of the class described, a knob mounted for rotation, a lock spindle mounted coaxially of said knob, a primary lock mechanism in said knob, a rotatable key plug in said primary lock mechanism, a throw pin on the end of said key plug movable in a circular path by rotation 55 of the key plug and normally positioned in substantially axial alignment with said knob and said lock spindle, a crank member secured on the end of said lock spindle, and a link positioned between said crank member and the end of said 60 key plug, said link being pivotally connected at one point with said throw pin and being pivotally connected at another point with said crank member whereby said knob may be turned without turning said lock spindle and said lock spindle 65 may be turned by turning said key plug. 70
